FIG. 1

FIG. 2

Edward S. Savage, INVENTOR.
BY David Simms, his ATTORNEYS.

UNITED STATES PATENT OFFICE.

EDWARD S. SAVAGE, OF ROCHESTER, NEW YORK.

SPARK-PLUG.

1,359,923.

Specification of Letters Patent. Patented Nov. 23, 1920.

Application filed August 25, 1919. Serial No. 319,705.

To all whom it may concern:

Be it known that I, EDWARD S. SAVAGE, a citizen of the United States, and resident of Rochester, in the county of Monroe and 5 State of New York, have invented certain new and useful Improvements in Spark-Plugs, of which the following is a specification.

The present invention relates to spark 10 plugs, and more particularly to the type in which an auxiliary sparking means is provided visible from the exterior of the cylinder, so that the operation of the spark plug may be ascertained without removing the 15 spark plug from the cylinder. An object of this invention is to provide a construction in which the auxiliary sparking means will not act if the spark is not occurring between the electrodes, notwithstanding the fact that 20 a short-circuit is provided between the insulated electrode and the metallic plug or support. Another object of the invention is to provide an auxiliary sparking means which may be shifted on the spark plug 25 in order that it may be visible from any desired direction.

To these and other ends, the invention consists of certain parts and combinations of parts all of which will be hereinafter 30 described, the novel features being pointed out in the appended claims.

In the drawing:-

Figure 1 is an axial section through the spark plug; and 35 Fig. 2 shows the spark plug in side elevation.

Heretofore it has been suggested to provide a spark plug with an auxiliary sparking means visible from the exterior of the cylinder, but in all known constructions, in 40 which such auxiliary means is provided, the auxiliary sparking means will act at times when a spark between the electrodes is not being produced. As an instance, if a carbon 45 coating covers the exposed surface of the insulator, an electrical circuit will exist through the carbon coating between the electrodes, permitting a current to pass which will not be distinguishable, in the auxiliary 50 sparking means, from a circuit produced from a spark jumping between the electrodes. In this invention the auxiliary sparking means will only act when a spark jumps between the two electrodes, as the exposed 55 insulating surface between the two

electrodes is greater than the exposed insulating surface between either of the electrodes and the metallic plug or support, and as a consequence a circuit through the carbon on the insulator between one of the electrodes and the metallic support will short-circuit the auxiliary sparking means. 60

The invention further provides for the mounting of the auxiliary sparking means so that the auxiliary spark may be shifted 65 in order that it may be viewed from the desired side of the engine.

Referring to the embodiment of the invention herein shown, 1 indicates the metallic support or plug which has a central 70 opening and a reduced screw-threaded extension 2 adapted to be inserted in the cylinder. This plug carries two electrodes 3 and 4 insulated from each other and from the metallic support. This insulation is secured in this instance by providing an elongated insulator 5 arranged centrally in the plug with the electrode 3 centrally positioned therein. The insulator may be secured in the plug in any suitable manner, 75 but in this instance it has a surrounding annular rib 6 held between an internal shoulder 7 on the plug or support and an internal shoulder 8 formed on a collar 9 which is fitted in the outer enlarged end of the central opening through the metallic plug or support. The outer end of this insulator 5 carries the binding post 3^a electrically connected to the electrode 3, whereas the inner 80 end of the insulator is tapered at 10. The inner end of the central opening through the plug or support being cylindrically formed, there is thus provided a chamber or pocket 11 between the inner end of the insulator and the metallic plug or support 95 giving a wide surface on the insulator over which the current must travel in order to reach the metallic plug or support from the electrode 3.

The electrode 4 is insulated from the electrode 3 and the metallic plug or support 1 in any suitable manner. In this instance this electrode is eccentrically arranged with reference to the plug, and the insulator, and has its inner end turned laterally at 12, a 100 tubular insulator 13 surrounding the same throughout its length and being extended onto the laterally turned portion 12. The metallic support or plug 1 has at its inner end a hood 14 which partially surrounds the 105 110

projecting end of the terminal 4, and projects beyond the tapered end 10 of the insulator 5 with its base nearer to the center of the spark plug than the longitudinally extending portion of the insulator 13. The purpose of mounting the electrode 4 in the manner set forth is to provide a greater exposed insulating surface between the two electrodes 3 and 4 than is provided between the central electrode 3 and the metallic plug or support. By this arrangement, should the insulator become coated with carbon, current will travel from the electrode 3 to the metallic support or plug 1 before it will pass to the electrode 4 by way of the insulating surface, and in this way the electrode 4 will be short-circuited.

Arranged between the electrode 4 and the metallic support or plug 1 is the auxiliary sparking means. This means in this instance comprises a ring 15 arranged about the insulator 5 at the outer end of the metallic support or plug 1. Associated with this ring electrode 15 is a projecting electrode 16 which depends from the top wall of a housing 17, said housing being rotatably mounted upon the plug or metallic support 1 preferably through an annular flange 18 at its lower end engaged by a ring 19 secured to the plug above the flange, said ring in addition retaining said rotatable housing 17 to the plug. This housing 17 may have in its side wall a view opening closed by a lens 20, this view opening being directly opposite the depending electrode 16, so that when the housing is turned the electrode 16 and the view opening maintain their relative positions. The purpose of mounting the auxiliary sparking means so that the auxiliary spark may be shifted to any desired point about the spark plug is to permit bringing of the auxiliary spark into convenient position to be viewed from the desired side of the engine.

It will be apparent from the foregoing that as long as a spark is jumping from the electrode 3 to the electrode 4, an auxiliary spark will jump from the ring electrode 15 to the projecting electrode 16, the current then passing through the metallic housing 17 to the metallic support 1. However, should the exposed insulating surfaces between the electrode 3 and the metallic support 1 become coated with carbon to such an extent that current will pass from the electrode 3 to the metallic support 1, then the auxiliary sparking means will be short-circuited and, as a consequence, the user of the plug will be advised that the main spark is not occurring. As the distance over the exposed insulating surfaces between the electrode 3 and the metallic plug or support 1 is less than the distance over the exposed insulating surfaces between the electrode

3 and the electrode 4, no current can pass through the spark plug and at the same time produce a sparking of the auxiliary sparking means without a spark jumping from the electrode 3 to the electrode 4.

What I claim as my invention and desire to secure by Letters Patent is:—

1. In a spark plug, a metallic support, an electrode, an electrical connection between said electrode and said support provided with auxiliary sparking means, a second electrode, and insulation between the electrodes, the shortest distance over the exposed surfaces of such insulation being greater between said electrodes than between the second named electrode and the metallic support.

2. In a spark plug, a metallic support, an electrode, an electrical connection between said electrode and said support provided with a spark gap visible from the exterior of the plug, a second electrode, and insulation between the electrodes, the shortest distance over the exposed surface of such insulation between the electrodes being greater than the shortest distance over the exposed surface between the second named electrode and the metallic support.

3. In a spark plug, a metallic support, two main electrodes, both of which are insulated from each other and from the metallic support, and an electrical connection between one of said main electrodes and the metallic support embodying an auxiliary spark gap formed by two electrodes, one of which has an extended surface and is connected directly to one of the main electrodes, and the other of which is in the form of a point and is connected directly to the metallic support, said last named electrode of the auxiliary spark gap being shiftable with reference to the main electrodes and to the electrode having the extending surface so that the position of the spark gap may be shifted.

4. In a spark plug, a metallic support, two electrodes, both of which are insulated from each other and from the metallic support, and an electrical connection between one of the electrodes and the metallic support embodying an auxiliary spark gap formed by two electrodes, one of which directly connects with one of the main electrodes, and the other of which directly connects with the metallic support, one of said electrodes of the spark gap having an extended surface while the other is in the form of a point and is shiftable relatively to the main electrodes in a complete circle to change the position of the spark gap.

5. In a spark plug, a metallic support, two electrodes both of which are insulated from each other and from the metallic support, and an electrical connection between one of the electrodes and the metallic sup-

port embodying an auxiliary spark gap formed by two electrodes, one of which is directly connected to one of the main electrodes, while the other of which is directly connected to the metallic support, one of said electrodes having an extended surface while the other of said electrodes is in the form of a point and is freely movable relatively to the main electrodes so that the position of the spark gap may be readily shifted.

6. In a spark plug, a metallic support, two electrodes both of which are insulated from each other and the metallic support, and an electrical connection between one of the electrodes and the metallic support embodying a spark gap shiftable relatively to the metallic support and to the main electrodes.

7. In a spark plug, a metallic support, two electrodes carried by the support and insulated from each other and from the support, and an electrical connection between one of the electrodes and the support embodying an auxiliary spark gap, one of the electrodes of which is in the form of a ring normally fixed relatively to the support and to the electrodes and the other of which is in the form of a point shiftable relatively to the main electrodes and the metallic support.

8. In a spark plug, a metallic support, two main electrodes, insulating means by which the electrodes are insulated from each other and from the metallic support, means for securing said insulating means against movement in said support, and an electrical connection between one of the main electrodes and the metallic support embodying two electrodes forming a spark gap between them, one of said electrodes being directly connected to the metallic support while the other is directly connected to the main electrode, and one of said electrodes forming the auxiliary spark gap having an extended surface, and being normally fixed in relation to the part to which it is directly connected, while the other of said electrodes is in the form of a point and is shiftable relatively to the part to which it is directly connected and relatively to the securing means for the insulator.

9. In a spark plug, a metallic support, two electrodes mounted on said support to provide a spark gap between them, insulation between the electrodes and between the electrodes and the metallic support, and an electrical connection between one of the electrodes and the metallic support provided with auxiliary sparking means embodying an electrode in the form of a complete ring, and an electrode shiftable about the axis of

the ring to vary the position of the auxiliary spark gap.

10. In a spark plug, a metallic support having a central opening, an insulator arranged in said opening and projecting from the outer end thereof, two electrodes providing a spark gap between them, one of said electrodes being arranged centrally of said insulator and the other of said electrodes being arranged eccentrically with reference to the first named electrode and insulated from said first named electrode and the metallic support, a ring electrode surrounding the projecting end of the insulator and connected with the second mentioned electrode, and a shiftable electrode for cooperation with said ring electrode connected with the metallic support and mounted to turn about the axis of said ring to provide a shiftable auxiliary spark gap.

11. In a spark plug, a metallic support, two electrodes providing the main spark gap, insulating means between the electrodes and between the electrodes and the metallic support, a ring connected with one of said electrodes, a housing inclosing said ring and rotatably mounted on the metallic support and having electrical connection therewith, said housing being provided with a view opening, and an electrode eccentrically carried by said housing to provide a spark gap between such electrode and the ring.

12. In a spark plug, a metallic support, an electrode, an electrical connection between the electrode and the metallic support provided with an auxiliary spark gap, a second electrode, and insulating means between the two electrodes and between such electrodes and the support, said insulating means having a portion surrounding the first named electrode at a point inwardly beyond the metallic support and beyond that portion of the insulating means which surrounds the second named electrode.

13. In a spark plug, a metallic support having a hood projecting from the inner end thereof, two electrodes carried by said support, one of said electrodes lying partially within the hood and projecting laterally therefrom toward the other electrode, and insulating means between the electrodes and between the electrodes and the metallic support, said insulating means having a portion projecting beyond the hood about the laterally projecting portion of the electrode, and the exposed surface of the insulating means being greater between the electrodes than between the other of said electrodes and the metallic support.
